UNITED STATES PATENT OFFICE.

HORACE G. JOHNSTON, OF CORSICANA, TEXAS.

IMPELLER-PUMP.

1,090,066.

Specification of Letters Patent. Patented Mar. 10, 1914.

Application filed November 19, 1912. Serial No. 732,350.

To all whom it may concern:

Be it known that I, HORACE G. JOHNSTON, a citizen of the United States, residing at Corsicana, in the county of Navarro and 5 State of Texas, have invented certain new and useful Improvements in Impeller-Pumps; and I do hereby declare the following to be a full, clear, and exact description of the invention, such as will enable others 10 skilled in the art to which it appertains to make and use the same.

This invention relates to impeller pumps and has for an object to provide a pump embodying a new and improved form of impeller.

A further object of the invention is to provide a pump embodying a self-contained section having a propeller and coöperating parts, each section being independent from 20 other sections except in the matter of driving.

A further object of the invention is to provide self-contained impeller units being similar excepting the extreme unit, such 25 units being capable of being connected up in any desired number.

A further object of the invention is to provide an improved supporting head for the impeller pump with improved means for 30 withdrawing the line of pipe without removing the head.

A further object of the invention is to provide improved means for connecting the several units.

35 A further object of the invention is to provide an improved liner for the units with improved means for retaining such liner in operative position.

With these and other objects in view the 40 invention comprises certain novel constructions, combinations and arrangement of parts as will be hereinafter more fully described and claimed.

In the drawings: Figure 1 is a view of an 45 impeller pump made up of a number of units seen partly in side elevation and partly in section. Fig. 2 is an enlarged diametrical sectional view of the head. Fig. 3 is a diametrical sectional view of one of the units. 50 Fig. 4 is a top plan view of one of the couplings forming a part of one of the units. Fig. 5 is a view in perspective of one of the impellers. Fig. 6 is a view in perspective of a clutch for operating the impeller shown 55 at Fig. 5. Fig. 7 is a view in perspective of

a fragment of the hub of one of the impellers showing a slightly different means for attaching the shafting. Fig. 8 is a view in perspective of a section of shafting and clutch to coöperate with the clutch member 60 shown at Fig. 7. Fig. 9 is a top plan view of the follower showing deflecting blades.

Like characters of reference designate corresponding parts throughout the several 65 views.

The improved impeller pump which forms the subject matter of this application comprises a plurality of units shown as a whole at 10. The units comprise each a coupling 11 shown in enlarged detail at 70 Fig. 3 screw threaded at the lower end to receive the pipe section 12 and provided above such pipe section with blades 13 forming a spider having a bearing box 14 centrally thereof. The lower end of the bearing 75 box is provided with a follower 15 which together with the packing 16 forms a stuffing box for engaging the shaft 17 to prevent the passage of water and contained matter about the shaft into the bearing.

Above the spider an impeller is mounted comprising a hub 18, one or more fins 19 and an embracing and surrounding cylindrical band 20. Within the bearing box 14 a wood filler 21 is inserted, the bearing box 80 and wood filler being so proportioned that the hub 18 of the impeller abuts upon such wood filler as a thrust-bearing. In practice 85 it is found desirable to employ some exceedingly hard and comparatively non-porous wood such for instance as lignum vitae although the present invention is not restricted to the use of such wood.

About the circumferential band 20 of the impeller a liner 22 is employed such liner being composed of some flexible or elastic material such as leather, rubber or the like. In operation, the cylindrical band 20 would run in comparatively close relation to such liner 22, a space being shown in the drawings simply to indicate that there is opportunity for movement between the parts. The liner 22 rests upon an annular shoulder 23 in the coupling 11 with a follower 24 screwed into the end of the coupling 11 to hold such liner in position. The follower 24 is provided with blades 24' radially extending from the periphery but stopping short of the hub 18 with their lower ends curved as indicated at 24' so that the water in its 110

rotary movement impinges against the convex sides of said blades.

The follower 24 is screw threaded to receive the lower end 25 of the pipe so that 5 when the impeller unit is in position in a line of pipe the parts are associated as shown at Fig. 3. The impeller unit, however, consists of the coupling, the spider, the propeller and the shaft and pipe connected at 10 the bottom of the coupling. The shaft from above is connected with the hub of the impeller in such manner as to insure rotation of the impeller with the shaft but to permit longitudinal sliding movement. As 15 shown at Fig. 3 the shaft 17 is provided with a key 26 whereby the shaft is splined into the hub. As shown at Figs. 5 and 6 the hub is provided with a diametrical slot 27 and the shaft 17 is provided with a collar 28 rigidly secured thereto having wings 29 20 proportioned to fit into the slot 27 with the extremity 17' serving as a guide to enter first the central bore 30 of the hub.

Instead of employing a hub and clutch 25 such as shown at Figs. 5 and 6, however, the ordinary dental clutch may be employed as shown at Figs. 7 and 8, the collar 31 being provided with lugs 32 complementary to the lugs 33 carried upon the impeller hub 30 18, the extremity 17' of the shaft serving as a guide as above described relatively to Figs. 5 and 6.

Below the lower unit 10 any sort of strainer extremity, as indicated conventionally at 34 and pipe section 35 in Fig. 1, may be employed and the top unit is provided with a pipe section 36 which connects such top unit with the head shown at detail in Fig. 2. Such head comprises a base 37 which 35 is rigidly and permanently secured to the well or other covering indicated at 38 and is annular in form having a flange 39 with a central opening through which the top section of the pipe 36 is inserted. The top 40 section of pipe is provided with a threaded collar 40 having a flange 41 proportioned to bear upon the annular flange 39 with a gasket 42 introduced between the flange to produce a water-tight joint. Above the base 45 37 a housing 43 is erected having a discharge connection 44 and a cover member 45. The cover member 45 is provided with a bearing 46 through which the shaft 17 extends with a stuffing box 47 provided to produce a water-tight joint. Upon the upper end of the shaft 50 17 a pulley 48 is employed by which power is transmitted to the shaft 17 and the several units connected therewith below the head. To remove the connected units it will not be 55 necessary, therefore, to remove the entire head but the cover member 45 is removed by the removal of the bolts 49 and the removal of such cover carries with it the top section 17 of the shaft. A short length of 60 pipe is now inserted into the housing and

inserted into the threaded ring 40, such length of pipe extending above the housing in position to engage the grappling and lifting appliances. The connected units are lifted by such lifting device until the first 70 unit is above the housing whereupon it is unscrewed and removed and the lifting process continued until all of the units have been removed from the housing.

To secure access to the stuffing box 47 a 75 cover 50 is secured upon the housing in the usual well known manner.

About the bearing 46 a boss 51 is provided producing a chamber 52 between such boss and bearing-box, the walls of the boss being 80 higher than the top of the bearing box so that oil contained within the chamber 52 is in position to lubricate the bearing. To supply lubricant to the chamber 52 the cover 45 is provided with a passage 53 which extends 85 from the periphery of such cover to the bearing 46 with a lateral 54 leading to the chamber 52. Any convenient way of supplying oil to the passage 53 may be employed, here shown conventionally as a pipe 55 and oil 90 cup 56. It will be apparent that even when the oil in the chamber 52 is lower than the top of the bearing 46 oil will still feed through the lateral 54 and the passage 53 into the bearing.

In operation the head will be located over the pumping position, the cover 45 removed and units coupled together and inserted through such housing until the lower unit has been inserted a sufficient and desired 100 distance into the water when the cover will be placed in position with the top shaft section engaging the first unit and the power applied which will, as will be apparent, rotate the impellers in all of the several units 105 forcing water upwardly, as indicated by the several arrows, the spider blades 13 and 24' serving to prevent undue rotation of the water within the pipe and presenting the water to each impeller moving substantially 110 longitudinally of the pipe until discharged. It will be apparent also that the members of each unit will be carried and supported wholly upon the coupling of that particular unit so that the shaft section connected with 115 the pulley 48 is not required to support the entire line of shaft with its associated impellers as is done in ordinary impeller pump construction. It will be apparent also that the several units are wholly interchangeable and that more or less units may be added or taken away as circumstances may require by the simple process of removing a unit or removing the top pipe section 36 and adding a unit.

I claim:

1. In a pump, a unit comprising a coupling, a spider within the coupling, an impeller mounted to rotate upon the spider, a liner rigidly connected with the walls of 150

the coupling and surrounding the impeller, and a pipe and shaft extending below the coupling.

2. In a pump, a unit comprising a coupling, a bearing box concentric with the coupling supported by radial blades, a bearing member located within the bearing box, an impeller mounted above the bearing and comprising a hub abutting the bearing member, and means carried by the hub for slidably engaging a superposed shaft, said bearing box having a bore of substantially the same diameter as the hub and said bearing member being of corresponding diameter.
- 15 3. In a pump, a coupling, a rigidly mounted liner countersunk from the inner wall of the coupling, and an impeller mounted to rotate adjacent the liner, such impeller comprising a cylindrical band and a fin 20 within the band.

4. In a pump, a rigid structure comprising a tube, a tubular coupling member connected therewith, and a liner having an uninterrupted bore mounted within the coupling; an impeller permitting the passage 25 of fluid therethrough, and including an outer tubular portion having approximately the diameter of the tube and liner and movable independently and longitudinally 30 thereof.

5. In a device of the class described, a pump cylinder comprising a pipe coupling provided upon its interior with an annular shoulder, a flexible liner disposed within the coupling and resting upon the shoulder and a follower inserted into the coupling and engaging the liner, the inner walls of the liner, follower, and shoulder forming a substantially continuous surface.

- 40 6. In a device of the class described, a pump cylinder comprising a pipe coupling having an annular shoulder extending interiorly of the coupling, a liner composed

of flexible material within the coupling and bearing upon the shoulder at one edge, and 45 a follower inserted into the coupling and bearing against the edge of the liner opposite the shoulder, the inner walls of the liner, follower, and shoulder forming a substantially continuous surface.

50 7. In a pump, a head comprising a base and superposed housing, said base being provided with a central circular aperture, a ring proportioned to be inserted into the aperture and having an outstanding flange 55 proportioned to bear upon the base and prevent the ring passing through the aperture, said ring being screw threaded internally to engage a pipe section from either end.

8. In a pump, a head comprising a base, 60 a superposed housing and a removable cover for the housing, said base being provided with an inwardly extending annular flange producing a central aperture and an internally threaded ring proportioned to be inserted into the aperture and provided with 65 a flange proportioned to bear upon the flange of the base, said ring being proportioned to pass through the top of the housing when the cover is removed.

70 9. In a pump, an impeller member provided with a hub having a central shaft receiving socket and abutments located upon opposite sides of the central aperture in combination with a clutch member having a 75 shaft to engage in the shaft aperture and abutments extending outwardly from the shaft positioned to engage the abutments of the hub.

In testimony whereof I affix my signature 80 in presence of two witnesses.

HORACE G. JOHNSTON.
